2 Claims. (Cl. 220—91)

This invention relates to a means for securing handles to containers. More particularly, this invention relates to flexible ears for securing handles to containers.

At the present time, ears which are generally employed are unsatisfactory since they form lose fits with the edge of the container. This is due to the fact that the ear, when attached, has a slightly smaller diameter than the diameter of the container hole. Through normal use of the container, this fit becomes looser due to the friction caused by movement of the ear relative to the container wall. Eventually, the hole in the container becomes so large as to render the container unfit for use.

The present invention provides for a flexible ear assembly which insures a tight fit when it is attached to the container. The present invention also provides for an ear construction which substantially eliminates any movement of the ear relative to the container.

The present invention provides for a flexible two-piece ear construction wherein one piece fits into a recess of the other piece to cause the piece in contact with the container wall to expand slightly. The first piece when in use is inserted through a hole in the container wall from the inside of the container, and is in contacting relationship with the edge of the container hole. The second piece of the ear is then inserted into the recess in the protruding neck of the first piece to cause the first piece to expand slightly thus forming a tight fit with the hole edge.

Referring to the drawing, the first piece 1 is inserted through the container wall 5 from the inside of the container. The handle 6, which at the attaching end is formed into a loop, is slipped over the protruding neck portion 3 of the first piece. The second piece 2, is then inserted into the recess of the first piece 1 to form a tight fit.

In one preferred form of the invention, the second piece neck portion 4 has, at a point intermediate in its length, a slightly larger outside diameter than the inside diameter of the first piece neck portion. This insures a tight fit between the two pieces of the ear and also insures a tight fit between the first piece 1 and the wall 5 through the expansion of the first piece 1.

In another preferred form of the invention, the outside surface neck portion of the second piece 2 around its circumference at the point of larger diameter and the inside circumference of the first portion neck piece are deformed to function as an additional locking means when the two pieces are joined. One specific embodiment of such a surface deformation locking means is a slight recess around the circumference of the second piece 4 neck portion with a corresponding slight ridge around the inside circumference of the first piece neck portion 3 which fit together when the two pieces are joined. The same desired result is accomplished when the slight ridge 7 is located on the second piece neck portion 4 and the slight recess 8 is located inside the first piece neck portion 3. A series of complementary ridges or recesses on the two mating surfaces of the first and second piece neck portions also accomplishes the desired additional locking function. This complementary surface deforma-

2

tion locking means eliminates any tendency of sliding between the two pieces which may be caused by the larger diameter of the second piece neck portion 4.

The second piece neck portion 4 may be either solid or hollow. When the second piece neck portion is hollow, the wall thickness must be sufficient to give the required strength to expand the first piece. Also, when the second piece neck portion 4 is hollow, it is preferred that the larger outside diameter be located at a point near the head of the second piece 2, so as to cause the leverage action, due to the larger diameter, to act to expand the first piece 1.

As was previously stated, the ear of the present invention must be slightly flexible to promote expansion of the first piece, to insure a tight fitting relationship between it and the wall container and yet be strong enough to support the weight of the container. The ear of the present invention can be made of a high density plastic or rubber material such as high density polyethylene, high density polypropylene, high density nylon and the like. The two pieces of the ears of the present invention can be molded by processes which are obvious to one skilled in the art such as by extrusion and pressing to produce all embodiments of the invention as described above.

What I claim is:

1. A container of comparatively thin sheet material provided with a handle having a loop at each end thereof, said container having a pair of holes on opposite side-walls thereof, a pair of ear constructions, each connecting one said loop of said handle to said container, each said ear construction comprising two pieces of resilient material, including a first piece having at one end a head larger than said hole in said container side-wall and a neck extending from said head through said hole, said neck having an outside diameter at least slightly larger than the diameter of said hole and not greater than the inside dimension of said loop, said neck also having a recess extending towards said head from an end opposite said head, and a second piece having a head portion with a diameter larger than the inside diameter of said loop of said handle and a neck portion disposed in said recess, said neck portion having an outside diameter slightly larger than the diameter of said recess to provide a tight fitting relationship with the inside surface of said first piece neck and expand said first piece neck against the edges of said hole, said neck portion of said second piece being formed with a surface deformation on its outer periphery and said neck of said first piece being formed with a complementary surface deformation on the inner peripheral surface of said recess so positioned that when said neck portion is disposed in said recess said surface deformations are in locking engagement holding said pieces together, said neck of said first piece extending through said hole and protruding out of said container to receive one loop of said handle, the head of said first piece abutting against the inside wall of said container, and said head portion of said second piece preventing end-wise removal of said loop from said neck of the first piece.

2. The container claimed in claim 1 wherein said surface deformation of said neck portion of said second piece is a ridge around the circumference thereof and said complementary surface deformation is a recess around the inside circumference of said recess in said neck of said first piece.
